PRINTING MACHINE

Walter T. Gollwitzer, Chicago, Ill., assignor to
Addressograph Company, Wilmington, Del., a
corporation of Delaware

Original application October 26, 1927, Serial
No. 228,229. Divided and this application
April 30, 1929. Serial No. 359,197

10 Claims. (Cl. 101—415.1)

This application is a division of my application Serial No. 228,729, filed October 26, 1927.

This invention relates to machines for printing letters and the like and its object is to provide a flexible printing form adapted to be easily mounted on a roll in the machine for printing a signature on the letter.

Another object of the invention is to provide a roll having novel and simple means for detachably securing a signature printing form thereon.

Another object of the invention is to provide a flexible printing form having novel and simple means for securing it in printing position on a roll in a printing machine.

And a further object of the invention is to provide novel and simple means for securing a flexible printing form on one side of a flexible supporting plate for detachable mounting on a roll in a printing machine.

In the accompanying drawing illustrating a selected embodiment of the invention,

Fig. 1 is a sectional view on the line 1—1 of Fig. 2.

Fig. 2 is a sectional view on the line 2—2 of Fig. 1.

Fig. 3 is a perspective view on the signature device with the backing partly pulled away for better illustrating the construction.

Fig. 4 illustrates another form of the signature device.

Referring to the drawing 5 is a roll adapted to be suitably mounted on an operating shaft 6. A flat spring 7 is fastened at one end by a screw 8 or other suitable fastening device to the roll and its other end projects across an opening 9 in the roll and carries a screw 10 or other suitable fastening device which projects through said opening. The spring 7 is curved to fit more or less snugly against the inner face of the wall of the roll under normal conditions when the roll is not carrying a signature form, but when a signature form is mounted on the roll the spring is tensioned sufficiently to hold the signature form in proper position on the roll.

The signature form shown in Fig. 3 comprises an elongated flexible plate 11 preferably made of sheet spring steel provided with tapering openings 12, 13 which may be of triangular shape in its end portions. The opening in one end portion has an extension 13' for a purpose hereafter described. The plate is provided with openings 14 between its end portions and these openings are conveniently made in the form of elongated parallel slots. The signature form is made of rub-

ber or other suitable material and is mounted on the plate 11 over the openings 14. The form preferably comprises a strip 15 of rubber having the printing characters 16 embossed thereon. A backing 17 of cloth or other suitable material is cemented to the back of the plate 11 and to the signature form through the openings whereby the signature form is securely held in place on the metal plate. The signature form is readily applied to the roll by engaging the extension 13' with the stationary screw 8 and engaging the opening 12 with the movable screw 10. The screws 8 and 10 constitute retaining devices for holding the signature form on the roll. To facilitate engagement of the signature form with the screw 10 pressure should be applied upon the spring 7 by means of the thumb through the opening 9 to depress the spring which has the effect of moving the screw 10 to the right, Fig. 1, where it will more easily enter the opening 12, 75 after which pressure on the spring is released and the head of the screw will retainedly engage the opening 12 as the spring springs back towards normal position and will hold the signature form snugly and securely in place against the roll. To remove the signature form it is only necessary to apply pressure by the thumb through the opening 9 against the spring to move the screw to the right, Fig. 1, free from engagement with the edges of the opening 12, whereupon that 85 end of the signature plate will spring outward and the signature form is thereby released from the roll. The wall of the roll is preferably flattened on its outside face at 18, 18 and those flattened portions extend across the roll as chords 90 of the circle thereof and merge with the periphery so that the screws 8 and 10 which hold the ends of the signature form plate 11 are out of contact with the work upon rotation of the printing device inasmuch as the screws project 95 outwardly in an amount less than the thickness of the printing device. In Fig. 4 I have shown another signature form comprising an elongated rubber strip 19 having printing characters 20 embossed thereon and provided with a fabric backing 21. This form has eyelets 22 to engage the retaining screws 8 and 10.

The invention provides a novel and simple detachable printing form which is adapted to be easily and quickly mounted on the roll in a 105 printing machine without requiring the removal of any parts of the machine. This makes it possible to change the signature form frequently, if desired, without materially interrupting the operation or limiting the capacity of the machine. 110

Also, new signature forms may be supplied as frequently as may be required to replace worn or damaged forms and secure the best impression results. I have shown the invention adapted 5 for use in the machine of my original application but it may be adapted for and embodied in other machines and I do not restrict it to this particular machine but reserve the right to adapt it for and embody it in any printing machine 10 in which it may be used and to make changes in the form, construction and arrangement of parts within the scope of the following claims.

I claim:

- 15 1. A printing device for printing machines comprising a roll having an opening therein; a spring secured at one end within the roll and having its other end disposed opposite said opening; and a printing form detachably engageable with said roll and with the free end of said spring.

20 2. A printing device for printing machines comprising a roll having an opening therein, a spring secured at one end within the roll and having its free end disposed opposite said opening, a retaining device carried by the free end of the spring and projecting through said opening, a fixed retaining device on the roll spaced from the retaining device mounted on the spring, and a printing form detachably engageable with said retaining devices.

25 3. A printing device for printing machines comprising a roll having flattened portions on the periphery thereof and having an opening at one of said flattened portions, said flattened portions extending as chords of the circle of the roll and having the ends thereof merged with the periphery of the roll, a fixed retaining device at one of said flattened portions, a yieldable retaining device at the other of said flattened portions and projecting through said opening, and a printing form detachably engaged with said retaining devices.

30 4. A printing device for printing machines comprising a roll having flattened portions on the periphery thereof and having an opening at one of said flattened portions, a fixed retaining device at one of said flattened portions, a yieldable member mounted in said roll and carrying a retaining device extending through said opening, and a printing form detachably engageable with said retaining devices.

35 5. In a printing device for printing machines, a roll, a flexible printing form having centering openings therein, and means including retaining devices and a yieldable circumferentially extending arm, said retaining devices projecting from the periphery of the roll and engaging in said openings and cooperating with said arm to center and detachably secure the printing form on the periphery of said roll.

40 6. In a printing device for printing machines, a roll, a flexible plate having centering openings adjacent the ends thereof, a printing form

mounted on said plate between the openings, and securing means including retaining devices projecting from the periphery of said roll in an amount less than the thickness of the plate and form and a yieldable circumferentially extending arm; said securing means being adapted to cooperate with said openings to center and detachably secure the plate and form on the periphery of the roll. 80

7. In a printing device for printing machines, a roll having flattened portions on the periphery thereof extending thereacross as chords of the circle of the roll and having the ends thereof merged with the periphery of the roll, a flexible printing form, and means including retaining devices mounted at the flattened portions and projecting from the periphery in an amount less than the thickness of the printing form and adapted to detachably secure the printing form on the periphery of the roll. 85 90 95

8. A printing device for printing machines comprising a roll having an opening therein, a radially extending fixed retaining device on the periphery of the roll, a circumferentially extending yieldable arm fast in the roll and including a retaining device projecting radially through the opening, and a printing form detachably engaged with said retaining devices, said retaining devices projecting from the periphery of the roll in an amount less than the thickness of the printing roll and said arm centering said printing form on the roll and holding it taut thereon. 100 105

9. A printing device for printing machines comprising a roll having an opening therein, a radially extending fixed retaining device on the periphery of the roll, a circumferentially extending yieldable arm fast in the roll and including a retaining device projecting radially through the opening, and a printing form comprising a flexible support detachably engageable with said retaining devices to detachably secure the printing form on the periphery of the roll, said retaining devices projecting from the periphery of the roll in an amount less than the thickness of the printing form and said arm cooperating with said flexible support to center and hold the printing form taut on said roll. 110 115 120

10. A printing device for printing machines comprising a roll having an opening therein, fixed retaining devices on the periphery of the roll, a circumferentially extending yieldable arm fast in the roll and including a retaining device projecting through the opening, and a printing form having substantially triangularly shaped openings at its ends adapted for detachable engagement with said retaining devices to detachably secure the printing form on the periphery of the roll, said retaining devices and said arm cooperating with said triangularly shaped openings to center and hold the printing form taut on the roll. 125 130 135
